UNITED STATES PATENT OFFICE.

HARRY BERLIN, OF NEW YORK, N. Y.

STOP MOTION.

1,408,250.

Specification of Letters Patent. Patented Feb. 28, 1922.

Application filed July 29, 1920. Serial No. 399,752.

To all whom it may concern:

Be it known that I, HARRY BERLIN, a citizen of the United States, and a resident of the city of New York, borough of Brooklyn, in the county and State of New York, have invented a new and Improved Stop Motion, of which the following is a full, clear, and exact description.

The present invention relates to new and useful improvements in knitting machines, and it pertains more particularly to a stop motion therefor.

It is the primary object of the present invention to provide a mechanism in which if one of the threads of the machine breaks, the machine will be automatically stopped in order that the article made by the machine will be free of imperfections owing to a continuation of the knitting operation when one of the threads has been broken.

With the above and other objects in view, reference is had to the accompanying drawings, in which

Figure 1 is a fragmentary end view of a knitting machine showing the attachment in place thereon;

Fig. 2 is a detail view of the attachment operating mechanism;

Fig. 3 is a similar view showing the position of the parts when the device has been set in operation;

Fig. 4 is a similar view showing the position of the parts after the stopping operation has been completed.

Referring more particularly to the drawings, the frame of the machine is designated by the reference character 5, and said frame has extending transversely thereof a power shaft 6, upon one end of which is mounted a loose pulley 7 and a driving pulley 8. The loose pulley 7 and driving pulley 8 are adapted to be engaged by means of a belt 9, and when said belt 9 is engaged with the driving pulley 8, the mechanism of the machine is operated, it being stopped when the belt engages the loose pulley 7.

In carrying out the invention, a suitable bracket 10 is secured near the lower portion of the frame 5, and mounted for rotation in said bracket 10, is a shaft 11 driven by a chain 12 passing over sprockets 13 and 14. The sprocket 13 is carried by the shaft 11 and the sprocket 14 is carried by the power shaft 6. Mounted upon the end of the shaft 11 opposite to the sprocket 13, is a bevel

gear 15, and said bevel gear 15 meshes with a bevel gear 16 carried by a revoluble disk 17. Secured to the revoluble disk 17 and projecting from the periphery thereof, is a rigid finger 18, the purpose of which will be hereinafter described.

The reference character 19 designates a bracket projecting from one of the members of the frame, and it is to be understood that there is one of these brackets at each end of the machine. Revolubly mounted in the brackets 19, is a shaft 20, and said shaft carries a revoluble disk 21. The revoluble disk 21 is provided on its face with a pin 22, and pivotally secured to the face of the disk, as at 23, is a finger 24, a stop 25 being provided to limit the pivotal movement of the finger 24. Interposed between the pivoted finger 24 and the hub of the revoluble disk 21, is a coil spring 24', said spring serving to maintain the pivoted finger 24 at all times against the stop 25.

Projecting vertically in parallelism with the end members of the frame, is a rigid rod 26, said rod 26 being mounted in guide bearings 27. Secured to the lower end of the rigid rod 26, is a foot 28 adapted to lie in the path of the pin 22.

Pivotsly secured to a standard 29 carried by the frame 5, as at 30, is a trigger lever 31, and one end of said trigger lever 31 is provided with a projection 32 adapted to engage the upper end of the rigid rod 26 as indicated by the reference character 33.

A rod 36 suitably mounted in brackets 34 and 35, has adjustably secured thereto a collar 37. Secured to the rod or shaft 36, is a second collar 38, and interposed between said collar 38 and the bracket 35, is a spring 39, which spring serves to move the rod 36 in its bearings 34 and 35. Carried by the rod 36 is an arm 40, and said arm has a rigid extension 41 sliding in a bearing 42 to serve as a guide for the rigid rod 36. This rod 36 carries on its outer free end, the arm 43 of a belt-shifting mechanism, said arm carrying two spaced arms 44, between which the belt passes in traveling over either the loose pulley or driving pulley 7 and 8, respectively.

Loosely mounted on the shaft 20, is a pan 45 and rigidly projecting from a bracket 46 carried by the frame 5, at each end of the machine, is a rigid arm 47. The rigid arms 47 carry a depending wall 48, the

lower end of which overlaps the angular outer edge 49 of the pan 45. This pan 45 is secured to the disk 21 in such a manner that as the pan rocks about the shaft 20, the disk will be rotated on said shaft, the purpose of which will be hereinafter referred to. An inclined plate 50 is rigidly secured to the frame and projects over the rear edge of the pan 45, the purpose of which plate will also be hereinafter shown.

10 The reference character 51 designates one of the threads leading through the machine, said threads being carried by spools positioned in any desired manner with respect to the machine. These threads run around guide rollers or rods 53 and 54 to the operating needles of the machine. Between the guide rollers or rods 53 and 54, a substantially U-shaped piece of metal 55 is suspended by each of the threads, and said U-shaped piece of metal is of sufficient weight to rock the pan 45 should the same fall thereon. These several U-shaped metal members are retained in position by reason 25 of their engagement with the guide roller or rod 54.

The above-described mechanism operates in the following manner: Assume for the purpose of illustration that the machine is 30 running and one of the threads 51 should break. This action would drop the U-shaped piece of metal carried by this thread and the same would be deposited in the pan 45. Upon the piece of metal falling in the pan 45, the pan is rocked to the dotted line position shown in Fig. 1 and to the full line position shown in Fig. 3. As the pan is rocked to the position mentioned, the disk 21 will be revolved to a point where the 35 pivoted finger 24 will lie in the path of the rigid finger 18 carried by the disk 17. This disk 17 being rotated by means of the shaft 11 and chain 12, will cause a rotation of the disk 21.

40 During the rotation of the disk 21, the pin 22 carried thereby will engage the foot 28 of the vertically-disposed rod 26. Upon reciprocation of the rod 26, the trigger lever 31 will be rocked about its pivotal point 30 until it disengages from the collar 37 on the shaft 36. Immediately the trigger lever 31 disengages the collar 37, the rod or shaft 36 is moved to the dotted-line position shown in Fig. 1, under the influence of 45 the coil spring 39, and the belt 9 will be shifted to the idle pulley 7, thus stopping the machine by reason of the fact that no power can be transferred to the power shaft 6 through the medium of the loose pulley 7.

60 The angularly disposed wall 50 heretofore mentioned is positioned as shown in order that the U-shaped pieces of metal 55 in falling towards the pan are prevented from entering into the machine, thus assuring 65 that the U-shaped pieces 55 will at all

times be deposited in the pan, and the wall 48 is provided to retain the U-shaped pieces in the pan.

From the foregoing it will be seen that each time one of the threads breaks, the machine is automatically stopped, thus attracting the attention of the attendant in order that he may secure the ends of the thread and set the mechanism for a subsequent operation.

Claims:

1. A stop motion comprising in combination with the power shaft of a knitting machine, a revoluble disk driven from said power shaft, a rigid finger carried by said disk, a second revoluble disk mounted adjacent the first-mentioned disk, means carried by said second-mentioned disk for engagement with the rigid finger of the first-mentioned disk, means for operating said second-mentioned revoluble disk to move the said finger-engaging means into the path of the finger carried by the first-mentioned revoluble disk, and means operated by the second revoluble disk for cutting off the power of said machine.

2. A stop motion comprising in combination with the power shaft of a knitting machine, a revoluble disk driven from said power shaft, a rigid finger carried by said disk, a second revoluble disk mounted adjacent the first-mentioned disk, a spring-pressed finger carried by said second-mentioned disk and adapted for engagement with the rigid finger of the first-mentioned disk, means for operating said second-mentioned revoluble disk to move the said spring-pressed finger into the path of travel of the finger carried by the first-mentioned revoluble finger, and means operated by the second-mentioned revoluble disk for cutting off the power of the machine.

3. A stop motion comprising in combination with the power shaft of a knitting machine, a revoluble disk driven from said power shaft, a rigid finger carried by said disk and projecting beyond the periphery thereof, a second revoluble disk mounted adjacent the first-mentioned disk, means carried by said second-mentioned disk for engagement with the rigid finger of the first-mentioned disk when moved into the path of travel thereof, means for operating said second-mentioned revoluble disk to move said finger-engaging means into the path of travel of the rigid finger carried by the first-mentioned revoluble disk, and means operated by the second-mentioned revoluble disk for cutting off the power of said machine.

4. A stop motion comprising in combination with the power shaft of a knitting machine, a revoluble disk driven from said power shaft, a rigid finger carried by said disk, a second revoluble disk mounted adjacent the first-mentioned disk, a resilient

finger carried by said second-mentioned disk for engagement with the rigid finger of the first-mentioned disk, means for operating said second-mentioned revolute disk 5 to move its resilient finger into the path of travel of the rigid finger of the first-mentioned revolute disk, a rigid lug carried by the second-mentioned revolute disk, and means adapted for engagement by said lug upon revolving movement of the second-mentioned revolute disk for cutting off the power of said machine.

HARRY BERLIN.
